OIL WELL PUMP VALVE

Homer Kirk Wasson, Mooringsport, La.

Application June 13, 1931. Serial No. 544,204

4 Claims. (Cl. 251—121)

The present invention relates to pumps and particularly to pumps designed and constructed for the elevation of oil from deep oil wells.

A large proportion of the crude oil derived from the earth is pumped to the surface by pumps positioned far under ground and operated by pump rods extending to the surface, sometimes several thousand feet in length. The pumps, positioned so far beneath the ground level and being therefore inaccessible, are constructed as ruggedly as possible as it is obviously an expensive matter to remove them for inspection or repair. They are also frequently operated in gangs from a single power source and, inasmuch as the wells in one group may vary widely in their daily capacity to deliver oil, the pumps should preferably be built of different capacities.

It has generally been the practice however to use pumps of practically the same capacity for wells which differ widely in productivity and as a result it frequently occurs that a pump having a capacity to pump say 300 barrels a day has been placed in a well having an output of say only 100 barrels per day. This means that the actual rate of flow of oil past the pump is relatively slow and, inasmuch as the oil carries sand and grit with it, it is quite possible when the oil flows slowly for considerable quantities of such sand to settle on the valve seat of the pump, resulting in scouring of the valve seat, thus leading to its early destruction and necessitating loss of time and the heavy expense of removing the entire pump rod from the well for the purpose of removing and replacing the valve seat.

In accordance with the present invention I provide a novel form of pump plunger having a valve seat so designed as to reduce to a minimum the possibility of its impairment by the collection of grit thereon, with subsequent erosion. The pump plunger is also provided with novel means for retaining the valve seat in position, for guiding the valve in its motion and for furthermore preventing access to the valve seat for packing material which may be dislodged from the pump packing, or other foreign bodies of considerable size.

In adapting the invention to different types of valve naturally the details and arrangement of the component elements of the invention may be considerably modified to suit varying conditions. Hence the invention is not limited to that exact form of valve plunger illustrated in the accompanying drawing by way of example.

55 In the drawing

Figure 1 is a side elevation of a pump plunger embodying the invention;

Figure 2 is an axial section therethrough;

Figure 3 is a perspective view of the valve seat; and

Figure 4 is an axial section through a valve seat similar to that shown in Figures 2 and 3 but having somewhat different dimensions.

The valve body is indicated at 10 and is seen to comprise a generally tubular metallic member having an axial aperture 11 for the passage of oil in the direction of the arrow A shown in Figure 2. Around the exterior of this valve body is positioned any suitable packing such as indicated generally at P and which is adapted to 65 make a fluid tight contact with the inner cylindrical wall of the pump chamber.

The reduced upper cylindrical end 10' of the body is exteriorly threaded to receive the interiorly threaded lower end of a cage 12. Mounted upon the annular upper end surface of portion 10' of the body is a valve seat member 13 having a central aperture 14 aligned with the bore 11 of the body and through which all of the oil or other fluid being pumped must pass 80 in the operation of the plunger. The lower end of aperture 14 is preferably conical as shown, the conical section leading into a cylindrical section which terminates at its upper end in an annular seating surface 13' formed to receive 85 with a fluid tight fit the hardened spherical valve 15. A coiled spring is indicated at 16, the upper end of this spring bearing against the cage 12 and the lower end bearing against the upper surface of valve seat 13. The spring functions to maintain the valve seat in position and also to guide the ball valve 15 in its rising and falling movements. The spring furthermore functions to prevent the entrance through apertures 12' of the cage, and into the chamber in 95 which the valve 15 is located, of many large particles of pump packing or other foreign element which may tend to settle through the column of oil to the neighborhood of the valve.

In operation, of course, the plunger is reciprocated vertically by the pump rod above the same, which is not illustrated. On the downward stroke of the plunger oil passes through the duct 11 and thereafter through the valve port 14 lifting valve 15 from the seat and escaping from 105 the cage 12 and passing into the pipe or valve casing, (not illustrated), above the plunger. On the upward stroke of the plunger the valve 15 seats and the column of oil above the plunger is lifted. By reason of the fact that the port 14 110

which extends through the valve seat 13 is relatively restricted at its upper end, the stream of oil passing through this port is caused to have a relatively high velocity and it is found that this high velocity of oil substantially prevents the deposition on the valve seat of any impurities such as sand or grit which may be contained in the oil. By forming duct 14 in such way that its lower end is conical, the stream of upflowing oil is caused to gradually increase in velocity as it approaches the more restricted section of duct 14 and when it passes the valve seat is moving at maximum velocity.

I contemplate the use, in wells of different capacities of valve seats having effective oil passage ports of different dimensions. Thus in Figure 4 is illustrated a valve seat 20, the port 21 of which is of smaller diameter than that shown in Figures 2 and 3 of the drawing. The valve seat 20 is substituted for that shown in Figure 2 where the pump is to be applied to a well of less capacity. Similarly valve seats having ports of larger or smaller diameter may be employed, depending upon the capacity of the well in which the pump is used but in all cases the effective diameter of the port passing through the valve seat is relatively restricted as compared with the ports through valve seats of the types which have been heretofore used or are now on the market, thus ensuring maximum velocity of oil flow past the valve and valve seat.

The valve seat may be easily removed by unscrewing the cage 12 from the body 10. The spring 16 is used at all times, regardless of the size of the valve seat port.

Having thus described the invention, what is claimed as new and desired to be secured by Letters Patent is:

1. In an oil well pump plunger, in combination, a body portion having an axial duct there-through, a cage attached thereto, a valve seat supported by the body and having a port concentric with the duct, the diameter of the port in the valve seat being less than the diameter of

said duct, a valve movably retained in said cage and adapted to seat on said valve seat, and a coil spring surrounding said valve and serving as a guide for the latter, said spring engaging said seat to retain the same in operative position.

2. In an oil well pump plunger, the combination with a body having an axial duct there-through, of a cage carried by said body, a removable valve seat supported by the body and having a port therein communicating with said duct, a valve movably retained in said cage and adapted to seat on said valve seat to close the port therein, a coil spring surrounding and guiding said valve, said spring acting between said cage and said seat to retain the latter in position.

3. In an oil well pump plunger, in combination, a body portion having an axial duct there-through, a cage attached thereto, a series of interchangeable valve seats, each having a port therein, the ports being of varying diameters less than the diameter of the duct, means comprising a spring acting between said cage and seat for removably retaining a selected seat in position on the body with the port therein concentric with said duct, and a valve movably retained in said cage, guided by said spring, and adapted to seat on said valve seat.

4. In an oil well pump plunger, in combination, a body portion having an axial duct there-through, a cage attached thereto, a series of interchangeable valve seats, each having a port therein, the ports being of varying diameters less than the diameter of the duct, means for removably retaining a selected seat in position on the body with the port therein concentric with said duct, and a valve movably retained in said cage and adapted to seat on said valve seat, said seat retaining means comprising a coil spring exerting thrust between said cage and said seat and surrounding said valve to guide the latter into position on said seat.
